UNITED STATES PATENT OFFICE.

CHARLES HOWARD SMITH, OF SHORT HILLS, NEW JERSEY, ASSIGNOR TO INTERNATIONAL COAL PRODUCTS CORPORATION, OF RICHMOND, VIRGINIA, A CORPORATION OF VIRGINIA.

FURNACE-RETORT.

1,415,846.

Specification of Letters Patent. Patented May 9, 1922.

Application filed May 9, 1918. Serial No. 233,422.

To all whom it may concern:

Be it known that I, CHARLES HOWARD SMITH, a citizen of the United States, and a resident of Short Hills, county of Essex, 5 and State of New Jersey, have invented certain new and useful Improvements in Furnace-Retorts, of which the following is a specification.

The invention relates to a combined furnace and retort, frequently herein referred to as a furnace-retort. The furnace retort which is the subject of the present invention has been particularly designed and constructed to effect a partial distillation or 15 partial carbonization of coal in order to eliminate a part of the volatile hydrocarbons contained in the coal and in order to obtain a uniformly but partially distilled residue.

20 In the preferred embodiment of the invention the retort is in the form of a longitudinally extending tubular member closed at each end and has therein means for mixing and conveying the material that is charged into the retort at one end, to wit, the charging end, toward the other or discharging end of the retort. The retort is heated exteriorly and in such a manner that the coal or charge therein is uniformly but 25 progressively heated as it moves along the retort; this uniform but progressive heating being dependent to a certain extent upon the manner in which the charge is mixed and conveyed along the retort.

30 One of the objects of the present invention is to construct the heating means that is exterior of the retort in such a manner that the heat conditions in any transverse portion of the retort are under the control of 35 the operator. The major portion of the furnace-retort proper is of masonry and the mixing and conveying means referred to preferably comprises parallel shafts having paddles thereupon and arranged so that the paddles on one shaft overlap the paddles on the companion shaft as the shafts are rotated. These shafts and paddles are located within the retort and extend through the walls at the ends of the retort or at 40 the ends of the furnace-retort, dependent upon which way the construction is considered.

An object of the present invention is to provide a construction whereby the weight and thrust of these shafts are not borne 55 or received by said end walls but so that said weight and thrust are borne by bearing members mounted or supported on the exterior of or independent of the end walls 60 of the furnace-retort proper.

According to the present invention there is also provided means between the shaft construction—and it will here be remarked that the shaft construction may be broadly construed to include not only the shafts 65 but the bearing members therefor—whereby any openings in the end walls through which the shaft construction passes are sealed against the entrance of air to the interior of the retort or against the escape 70 of gases from the retort. In other words, there is a gas-tight joint at this place. The openings through which the shaft construction passes are somewhat larger than the shaft construction therein to allow for 75 expansion and contraction. This sealing means is also constructed so that the seal or air-tight joint is maintained under varying conditions of expansion and contraction.

Another object of the invention is to provide a furnace-retort construction that will facilitate building and repairing and that will also permit an inspection of the interior of the furnace-retort.

Another object of the invention is to provide a construction wherein the several parts can be readily assembled into a complete operative whole.

In a furnace for treating coal it is advantageous in many respects to employ a recuperator for heating the air to support combustion. A recuperator is a device whereby outgoing hot products of combustion or waste gases can be employed to effect a heating of the incoming air to support combustion by an interchange or transference of heat through walls of the recuperator that serve to separate the passageways through which the outgoing gases flow from the passageways through which the incoming air flows.

According to one phase of the present invention the recuperator constitutes a lower portion of or foundation for the fur-

nace-retort proper and there are provided ducts or passageways in the masonry construction of said furnace-retort proper whereby the hot incoming air received from the recuperator can pass to the combustion chamber of the furnace-retort and whereby the products of combustion can flow from the combustion chamber to the recuperator.

According to some phases of the present invention the combustion chamber is subdivided into a series of combustion flues arranged along the longitudinally extending retort. The heat conditions within each of the flues are controllable as will herein appear and this provides a construction wherein heat conditions along any transverse portion of the retort can be controlled.

A further object of the present invention is to provide a construction whereby furnace-retorts can be built in batteries and according to one phase of the present invention such a construction is facilitated by allowing expansion joints or spaces between adjacent side walls of adjacent furnace-retorts proper.

The invention relates to the features of construction above referred to as well as to other features, all of which are herein-after clearly described and set forth in the appended claims.

As showing a specific embodiment of the invention reference is made to the accompanying drawings forming a part of this specification and in which drawings,

35 Figure 1 is a vertical transverse view of a portion of a battery of furnace-retorts each having a recuperator. In this view there is shown in cross-section a furnace-retort proper supported by a recuperator construction below it. This figure is a view taken as on the plane indicated by the lines 1-1 of Figure 2, 3, 4 or 5.

Figure 2 is a view taken substantially on the line 2-a-b-c-d-2 of Figures 1 and 45 8 looking in the direction of the arrows. It is not, however, an exact view taken on this line for the reason that there is included in Figure 2 the piping which leads from the upper interior portion of the retort and 50 which piping is at one side of the place where the section is taken. It will be noted that in Figure 2 the parts are shown on a smaller scale than in either Figure 1, or in Figures 3 to 9 inclusive.

55 Figure 3 is a horizontal sectional view taken as on the plane indicated by the line 3-3 of Figures 1 and 4. All parts which are shown on this plane are in section, with the exception of the companion parallel 60 shafts, the paddles carried thereby, the bearing members for the shafts, and the driving mechanisms for actuating the shafts.

Figure 4 is a vertical, longitudinal, transverse view taken as on the plane indicated by

the line 4-4 of Figures 1 and 5 looking in 65 the direction of the arrows.

Figure 5 is a horizontal, transverse, sectional view taken as on the plane indicated by the line 5-5 of Figures 1 and 2 looking in the direction of the arrows. 70

Figure 6 is a complete view taken as on the planes indicated by the broken line 6-f-g-6 of Figure 1 looking in the direction of the arrows. In other words, the left-hand portion of Figure 6 is a view taken as 75 on the line 6-f of Figure 1, or 6'-6' of Figure 4 looking in the direction of the arrows; while the right-hand half of the figure is a view taken as on the plane indicated by the line g-6 of Figure 1 or 6"-6" of 80 Figure 4 looking in the direction of the arrows.

Figure 7 is a horizontal sectional view looking downwardly and is a view taken as on the plane indicated by the line 7-7 of 85 Figure 4.

Figure 8 is a vertical transverse sectional view taken as on the plane indicated by the line 8-8 of Figure 2 looking in the direction of the arrows. 90

Figure 9 is an end view of a discharge end portion of a battery of retorts.

Figure 10 is a view of the outer or exterior portion of a main end plate or main end plate casting. 95

Figure 11 is a view of the outer portion of a small end plate casting used in conjunction with the main end plate casting shown in Figure 10.

Figure 12 is a sectional view of the main 100 end plate casting and is a view taken as on the plane indicated by the line 2-2 of Figure 10 looking in the direction of the arrows.

Figure 13 is a view partially in section 105 of the assembled main end plate casting and the small end plate casting. A part of Figure 13 is a view taken as on the plane indicated by the broken line 13-p-q-13 of Figure 10 looking in the direction of the 110 arrows.

Figure 14 is a sectional view of the assembled main and small end plate castings and some of the parts associated therewith. The section of the assembled end plate castings 115 is a view taken as on the planes indicated by the line 14-14 of Figure 10. In Figure 14 there is also shown an end of the paddle carrying shaft, an end of the bearing member which supports the shaft, and sealing means employed between the bearing member on the one hand and the main end plate casting on the other to prevent the inflow of air to the interior of the retort or to prevent the escape of gases from the interior of the retort. 120

Figure 15 is a sectional view of the main end plate casting shown in Figure 10 and

the small end plate casting shown in Figure 11 when assembled, and is a view taken as on the plane indicated by the line 15—15 of Figure 10 looking in the direction of the 5 arrows.

Figure 16 is an edge view of the assembled main end plate casting and small end plate casting.

Figures 17 and 18 are end and sectional 10 views, respectively, of a gland which constitutes a part of the sealing means between the end plate casting and the bearing member for the shaft.

Figure 19 is an assembled view of the 15 metal parts that provide the discharge conduit construction. In this view there are shown an upper discharge casing or upper throat member, a rotary valve and casing therefor, which valve casing is sometimes 20 referred to as an intermediate discharge casing, a lower tapering throat member, or lower discharge casing as it may be called, a door at the lower end of said tapering casing, parts for maintaining the several casings and parts above referred to in assembled position, and also other mechanisms or 25 means for maintaining the discharge casing as a whole in position.

Figure 20 is a part sectional view and part 30 exterior rear view of the discharge conduit construction shown in Figure 19.

Figures 21, 22 and 23 show, respectively, an end or side view, a rear view, and a front view of the intermediate discharge casing or 35 valve casing construction.

Referring now to the drawings in detail, the furnace-retort is designated by 1 and comprises the retort 2 and the furnace 3, all of which may be considered as having vertically and transversely extending end walls 4 and 5, vertically and longitudinally extending side walls 6 and 7 that extend from end wall to end wall and are connected thereto, the base construction 8 that extends from 45 end wall to end wall and from side wall to side wall, and the roof construction 9 that extends from end wall to end wall and from side wall to side wall. The end wall 4 may be referred to as the front or charging end, 50 while the end wall 5 may be referred to as the rear or discharging end wall.

The furnace-retort construction just described may be termed the furnace retort proper. The furnace-retort proper may be 55 supported in any suitable manner; in the construction shown it is carried by a recuperator construction 10, which recuperator is provided for raising the temperature of the air supply to the furnace by heat from 60 the waste gases that leave the furnace. The recuperator has vertically and transversely extending end walls 11 and 12, and the end walls of the recuperator and the end walls 65 of the furnace-retort proper in effect become

continuations of each other. The recuperator also has vertically and longitudinally extending main side walls 13 and 14 and spaced tunnel side walls 15 and 16, the latter of which provide between them a longitudinally extending tunnel 17 large enough for 70 an operator to enter, in order to control certain valves and dampers as will hereinafter appear. The recuperator also has vertically and longitudinally extending partitions or intermediate walls 18 that serve to separate 75 a series of air ducts, as A, from a series of waste gas ducts, as B.

An inspection of the drawings will make it clear that these ducts are provided between adjacent vertically and longitudinally 80 extending walls of the recuperator and are in part defined by means of horizontally extending partitions or diaphragms, as 19, that cause the air or gases flowing through any set of ducts to take a sinuous path. The 85 sinuous path of the air flowing inwardly through the recuperator is indicated by the full line arrows (straight and curved) of Figure 4, while the path of the waste gases flowing outwardly through the recuperator 90 are indicated by the broken curved arrows in the same figure.

From some points of view the recuperator may be considered a part of the furnace of the furnace-retort and this view is more or 95 less justified from the fact that the recuperator masonry construction and the furnace construction merge into each other, and also in view of the fact that the recuperator has 100 an important part to play in the operation of the furnace.

From another point of view the recuperator may be considered as a distinct apparatus and in a way independent of the furnace, the function of the recuperator being 105 to receive waste gases given off or discharged from the furnace and conveyed to the recuperator and to employ these waste gases as a means for supplying heat that is transferred to air flowing inwardly through the 110 recuperator on its way to the furnace of the furnace-retort. As far as the purposes of this case are concerned, however, it matters little which view is taken. It will be here pointed out that where applicant refers to 115 the furnace-retort he desires it to be understood that he does not imply a construction wherein a recuperator must be used, as the furnace-retort referred to herein may or may 120 not have a recuperator construction in connection therewith.

An inspection of Figure 1 will also make it clear that the recuperator construction 10 for each furnace embodies in effect two separate recuperators, one for the right-hand 125 half of the furnace and the other for the left-hand half of the furnace. It will also be observed that the recuperator main side

walls 13 and 14 are the main side walls for recuperators on the opposite sides thereof when the retort-furnaces are built in batteries. The manner in which waste gases 5 are brought to the recuperator and the manner in which the hot air is conveyed from the recuperator to the furnace will hereinafter be described in detail.

From an inspection of Figure 4 it will be 10 noted that the air leaving the recuperator is nearest to the gases just entering the recuperator with the result that the air can attain a higher degree of heat than it is otherwise possible to attain. In other words, 15 the incoming air flows in a counter direction to that in which the outgoing gases flow.

From what has preceded and from an inspection of the drawings, and particularly Figures 1, 4 and 6, it will be apparent that 20 the recuperator construction provides a firm and solid foundation or support for the furnace-retort proper. The base construction 8, the side walls 6 and 7, and end walls 4 and 5 all merge into each other with the result that 25 there is a continuous masonry construction that is supported upon the recuperator construction 10. The retort 2 of the furnace-retort 1 is provided between the end walls 4 and 5 and within a tubular inner wall construction 30 which extends longitudinally from end wall to end wall, thereby providing what is herein referred to as a longitudinally extending retort or retort chamber. The tubular inner wall construction 35 35 is in cross-section a modified cylinder and more specifically it is of inverted heart shape. This inner wall construction 20 is supported intermediate its ends and at many places throughout its length by vertically 40 and transversely extending partitions or diaphragms 21. The roof construction 9 heretofore referred to extends horizontally, both longitudinally and transversely, from end wall 4 to end wall 5 and from side wall 6 45 to side wall 7 and in effect becomes a part of the same masonry construction which defines the walls and base portion of the furnace 3.

The combustion chamber C is provided on the exterior of the tubular inner wall construction 20 between the latter on the one hand and the base construction 8, the side walls 6 and 7 and the roof 9 on the other hand. This combustion chamber C as a whole is divided into what may be considered 50 two smaller combustion chambers by means of vertically and longitudinally extending partitions 22 and 23. One of these smaller combustion chambers designated by 24 is located at the left-hand side of the furnace 55 while the other smaller combustion chamber designated by 25 is located at the right-hand side of the furnace.

It will be observed that the vertically and 60 longitudinally extending partition 22 extends from the base construction 8 to the

under exterior portion of the tubular inner wall construction 20 and the vertically and longitudinally extending partition 23 extends from the upper exterior portion of the tubular inner wall construction 20 to the 70 under side of the roof construction 9. The vertically and transversely extending partitions previously referred to subdivide the smaller combustion chambers 24 and 25 into what are hereinafter referred to as combustion flues, 26 and 27 respectively. The combustion flues 26 and 27 collectively constitute the combustion chamber C of the furnace 3.

Referring now to Figures 4 and 6, 28 80 designates a passageway leading from the upper portion of the recuperator 10 to a relatively large horizontally and longitudinally extending main duct or conduit 29 from which there branches small horizontally and 85 transversely extending ducts or passageways 30 corresponding in number to the combustion flues at the particular side of the furnace upon which the conduit 29 is located. These small branch ducts or passageways 30—each 90 controlled by a damper 32 that is operable from within the tunnel 17 (see Figures 1 and 2)—lead to corresponding upwardly extending ducts or passageways, as 31 (see Figures 1 and 2), each of which passageways 31 95 leads to the lower portion of a combustion flue corresponding thereto and in this way a regulated amount of air for supporting combustion is supplied to the combustion flues at each side of the furnace. 100

In Figures 1 and 2 there are shown a means for supplying fuel that is burned in the combustion chamber. The fuel supply is preferably gas received in the main supply pipe 33 and which flows therefrom 105 through valve-controlled branch pipes 34 corresponding in number to the combustion flues. As the air supply is under the control of the dampers 32 and the fuel supply is under the control of valves, as V, it will 110 be manifest that the combustion which takes place within each flue can be regulated and under the control of the operator when within the tunnel 17. In order that the heat within the tunnel will not be excessive 115 heat insulating brick 35 is provided in the tunnel side walls 15 and 16. The products of combustion or waste gases pass from the upper portion of each combustion flue (see Figure 1) as through passageway 36 that is 120 controlled by a damper 37 and through passageway 38 likewise controlled by a damper 39. These two damper-controlled passageways are provided for each combustion flue, as can be seen from an inspection of Figure 125 5. The passageway 36 opens into a common longitudinally extending conduit or passageway 40, while the passageway 38 opens into a branch conduit or passageway 41 that leads to said common longitudinally extend- 130

ing passageway 40. There is a set of these passageways at each side of the furnace and they are separated from each other so that the draft conditions at one side of the furnace will not affect the draft conditions at the other side of the furnace. Each of the dampers 37 and 39 can be positioned by a bar in the hands of an operator through an opening, as 42, when the cover 10 43 is removed. From the longitudinally extending passageway 40 the waste gases first pass horizontally and transversely through passageway 44, next downwardly through passageway 45, and thence to a horizontally 15 and transversely extending header opening or conduit 46 (see particularly Figures 4, 6 and 7) from which they flow into the uppermost passageway 47 of the recuperator 10. The piping 48 shown clearly in Figure 2 and also indicated in other figures is provided to conduct gaseous and hydrocarbon vaporous products given off from the coal or charge being heated within the retort. This piping leads to a hydraulic main, the 25 function of which is well known in the art. The upper portion of this piping 48 is preferably of metal, but the lower portion directly in the heat zone is preferably in the form of hollow blocks of high refractory material and can be constructed as 30 shown in Figures 2, 5 and 8. When a battery of furnace-retorts is constructed the end walls become continuous, as shown in Figures 3 and 5. The roof construction can 35 also be built continuous, as shown in Figure 1. In the operating of the furnace it is well known that the masonry construction has a substantial expansion when highly heated and in order that the interior portion of the retort will not become distorted, 40 due to expansion, an expansion joint or expansion space 49 is provided between adjacent side walls of adjacent furnace-retorts. This expansion joint or space is 45 clearly shown in Figures 1, 3, 5 and 6. A break or off-set is provided in the side walls of adjacent furnaces so as to facilitate the forming in said side walls vertically extending passageways 45. As the end 50 walls and roof do not become so highly heated they can be made continuous, as has been previously described. The end walls 4 and 5 and roof 9 each have a layer of heat insulating brick 50 and 51 to minimize 55 the radiation of heat. Each retort is provided with means for feeding or charging coal thereto, which feeding or charging means is shown in Figure 2. It comprises a hopper 52 and an enclosed worm or screw- 60 conveyer 53 which when rotated forces the coal into the interior of the retort and also seals the retort as against the entrance of air. This screw-conveyer can be operated in any suitable manner. Within each retort 65 there is means for mixing the coal or charge

therein and for conveying the charge from the charging end of the retort toward the discharging end thereof. This mixing and conveying means comprises a pair of companion parallel shafts 54 and 55 each carrying thereupon paddles, as 56. These shafts are arranged so that the paddles on one shaft overlap those on the companion shaft as the shafts rotate. The paddles are shaped to effect not only the mixing or agitating 70 just referred to but also to effect the desired conveying or forward movement of the charge. The retort construction also includes end plates or end castings 57 and 58 through which the shafts extend. The 75 shafts are carried by suitable bearing members 59 and 60, which bearing members enter openings in said end plates, as will be manifest from an inspection of Figures 2, 3 and 14. The bearing members and the shafts 80 may be broadly considered a shaft construction that extends through said end plates 57 and 58; the openings in the end plates are larger than the shaft construction 85 therein. In other words, in the specific form 90 of the invention shown the openings are larger than the portions of the bearing members therein.

In Figures 2 and 9 there is shown part of the platform construction that is employed 95 as a support for the bearing members. The platform construction for the bearing members 59 at the charging end of the furnace is designated by 61 and the platform construction for the bearing members 100 60 at the discharging end of the furnace is designated by 62. These platforms support the bearing members so that the shafts are not in any way carried by the end walls of the furnace-retort; in other words, all 105 weight or thrust of the shafts is carried by bearing members supported on the exterior of and independent of the end walls of the furnace-retort. The openings in the end castings are sufficiently large to allow any 110 expansion or contraction which may take place as the furnace-retorts are put in operative or inoperative condition. The end plate construction is shown in Figures 10 to 16 inclusive. A packing, as 63, is provided around each bearing member of the shaft construction and this packing cooperates with each bearing member and the end plate corresponding thereto in a manner to 115 seal the space between said bearing member and the end plate. The packing means 63 comprises a gland 64, such as shown in Figures 2, 14, 17 and 18, and other suitable packing material, as 65, for example, asbestos, indicated in Figures 2 and 14. The 120 bearing members can be adjusted on the supporting means so that the position of the paddles on each shaft relative to the interior portion of the retort can be regulated. The bearing member 59 at the charging end 125 130

of the furnace is the same, as far as adjustments are concerned, as the bearing member 60 at the discharging end thereof and a description of the means for securing an 5 adjustment of either of the bearing members will apply to the other. Each bearing member rests upon a bed-plate or foundation plate, as 66, which is secured in place by bolts 67. The bearing member, as 59, 10 is secured in place on its corresponding bed-plate, as by means of bolts 68 which pass through a washer-member or washer-members 69, holes 70 in bed-plate 66, holes 71 in the bearing member 59, and washers 72. 15 The holes 70 and 71 are considerably larger than the bolts passing through them whereby a substantial horizontal adjustment of the bearing members over the bed-plate can be effected. The bed-plate 66 has at each 20 side thereof an ear or lug, as 73, through each of which ears there passes an adjusting bolt, as 74. The bolts 74 extend in a horizontal direction and in a direction transverse of the axis of the shafts carried 25 in the bearings. The bolts 74 can be relied upon to obtain horizontal adjustment of the axes of the shafts. The inner ends of these bolts engage plates or pads 75 and serve to effect a horizontal transverse adjustment of the bearings and a consequent 30 horizontal transverse adjustment of the shafts relative to the tubular inner wall construction 20 within which the shafts are located. This horizontal adjustment is, of course, permitted only when the clamping 35 bolts 68 are loose enough to permit the adjustment to take place. If a vertical adjustment of the shafts relative to the tubular inner wall construction 20 is desired 40 this is accomplished by means of adjusting bolts 76 which pass through the bearing member, as 59, and engage the upper surface of the bed-plate 66. By properly turning the bolts 76 the adjustable bearing member 45 can be raised or lowered. If desired shims or full filling plates can be inserted in any place remaining between the bearing member on the one hand and the bed-plate therefor on the other at the end of the vertical 50 adjustment. When the vertical adjustment is finished the bolts 68 are tightened and the bearing members are thereby firmly secured in the desired position. The adjusting means just referred to has been 55 described in connection with the bearing and plate therefor at the discharge end of the retort and substantially the same construction is employed for the bearing members at the charging end of the retort. The 60 end plates through which the shafts extend and into which the bearings for the shafts extend are, as previously stated, clearly shown in Figures 10 to 16 inclusive. The end plates at opposite ends of the furnace are 65 substantially the same with the exception

that the end plate at the charging end thereof requires an opening through which the coal passes as it is fed by the screw-conveyer 53 heretofore described. Each end plate may be considered to have a vertically and transversely extending main or body member 77 which carries annular members 78 that extend inwardly toward the retort and that surround the bearings for the shaft. At the inner end of each of the 70 annular members 78 there is a flange construction, as 79, a part of which flange construction is employed to hold the end plate in the masonry end walls and part of which serve to protect the inner ends of the bearing members from the heat within the retort. At the outer or exposed side of the main or body member 77 there is provided a longitudinally extending portion 80 that is in the form of a modified U and this modified U 85 serves to connect a flange or face member 81 to the main or body member 77. The construction just described is frequently referred to as the main end-plate member or main end-plate casting. 90

In Figure 11 there is shown a small end-plate casting member 82 secured in place by bolts which pass through openings 83 into threaded openings 84, the latter of which are in the main end-plate casting. This 95 small end-plate casting 82 completes the face or flange of the end-plate construction, as it may be referred to. When the parts are all assembled the paddle carrying shafts (as 54 or 55) pass through the end plate casting, 100 as through openings 85. Bearing members, as 59, pass through openings 86 into spaces 87 provided in the end-plate castings to receive portions of the bearing members. 105

An inspection of Figure 14 will make it clear that there is a pocket 88 provided in the end-plate casting around each bearing and between the main or body member 77 on the one hand and the face members 81 and 82 on the other. In each of these pockets 110 there are located the sealing means 63 which comprises the gland 64 and the packing 65 heretofore referred to. Each gland is forced toward and held in operative position by means of adjusting or holding screws 90 115 that pass through threaded openings 91 and 92 in the face members 81 and 82 respectively. From an inspection of Figure 14 it will also be noted that the bearing members 120 and shafts can be moved in a direction transverse to that in which the shafts 54 and 55 extend without breaking the seal or joint that is provided between the bearing member, as 59, on the one hand and its corresponding end plate adjacent thereto on the other. The bearing members are hollow, as at 93, for cooling purposes. The shafting and bearing members therefor herein described may be broadly considered, as has been heretofore stated, as a shaft construc- 125 130

- tion that extends through the end plates and between which shaft construction on the one hand and the end plates on the other there is provided means for sealing the space that 5 is left between the shaft construction and the end plates to permit expansion and the required adjustment of the shafts and particularly the paddles carried thereby relative to the tubular inner wall construction of the 10 retort. The end plate at the charging end of the furnace is provided with an opening *co* through which the coal is fed by means of the screw-conveyer, in the manner heretofore described. Sight holes *sh* are provided at each side of the end plate. These 15 sight holes are arranged so that the lower interior portion of the retort can be inspected when the holes are open. These holes are normally closed by a cap *c* shown in Figure 14. The casing for the screw-conveyer 53 can be normally clamped in place to the flange *f* that is at the end of the construction which provides the charging opening *co*. The charging opening *co* 20 and sight holes *sh* are all located below the modified U-shaped member 80 of the casting and it will also be noted that the sight holes *sh* are located below the openings 85 through 25 which the shaft construction extends.
- 30 The construction of the means which provide the discharge passageway leading from the interior of the retort will now be described. The discharge passageway is broadly designated 94 (see Figure 2) and 35 an inspection of this figure, taken in conjunction with Figure 8, will make it clear that the upper portion of the discharge passageway is provided in a masonry construction and is sub-divided into two smaller passageways 95, 95. The passageways 95 lead to a common passageway 96 provided in a vertically extending tubular member 97 that constitutes a part of the upper discharge casing 98. This casing 98 also 40 has a horizontally extending plate 99 that rests upon I-beams 100 that in turn rest upon masonry construction 101 which may be considered to be a part of or an extension of the retort main side walls 13 and 14 heretofore described. The tubular member 97 extends in part above the upper edge of the plate 99, but most of the member 97 depends from the plate 99. These I-beams provide 45 the main support for the discharge casing construction clearly shown in Figures 2, 9, and 19 to 23 inclusive. The lower portion of the upper discharge casing 98 is provided with a flange 102 and it also has openings 103 carrying pipes 104 normally sealed.
- 50 Through these openings the interior of the conduit can be inspected and bars can be inserted to break up any coal residue that may happen to collect or lodge therein. The intermediate discharge casing is designated as 55 105 and comprises a body part 106 and a cover 107 that is normally held in place by bolts which pass through openings 108 and 109. Said intermediate member has flanges provided with bolt-hole openings that register with corresponding bolt-hole openings 70 in the flange 102 of the upper discharge casing 98 whereby the upper discharge casing and intermediate discharge casing are bolted together.
- Within the intermediate discharge casing 75 105 there is supported an angularly movable or rotary valve 111 that normally seals the discharge passageway when the valve occupies the position shown in Figures 2, 19 and 20. When the valve is given substantially 80 a quarter of a revolution (to a position adjacent to the cover 107) it opens the passageway and permits the material to pass from the upper discharge casing through the intermediate discharge casing 105 into the 85 lower discharge casing 112. The ends of this valve are supported on shafts 113 which are keyed to the valve so that when the shafts are turned from the exterior, as by any suitable means, the valve will necessarily 90 be turned. These shafts extend through bearings 114 that are provided in header members 115 that constitute a part of the intermediate discharge casing 105. The connections between the shafts 113 and the 95 angular movable valve 111 are such that they permit the valve 111 to be readily removed from the casing when the cover 107 has been removed. The lower discharge casing is secured to the intermediate casing by bolts 100 which pass through openings in the flanges 116, 117 that are respectively provided on the lower portion of said intermediate casing and the upper portion of the lower discharge casing. The lower discharge casing 105 is of sufficient size to provide what may be called a receiving chamber at the discharge end of the conduit and this casing, because of its tapering toward the delivery end thereof, is sometimes referred to herein as a 110 tapering lower throat member. The discharge end of this lower tapering throat member is normally sealed by a door 118, carried on a hinge 119, that is normally clamped in closed position. By means of 115 the valve 111 on the one hand and door 118 on the other it will be manifest that material can be discharged from the retort without allowing the entrance of any substantial amount of air to the interior thereof. The 120 lower end of the discharge casing construction as a whole is provided with a spring-supporting means 120, as clearly shown in Figure 19.
- The platform constructions 61 and 62 can 125 be made in any suitable manner to perform their desired function. In Figures 2 and 9 and they are shown as made of structural steel. As is usual in furnace constructions the side walls and end walls may be tied to-

gether as by vertically extending structural steel members and tie-rods, such as are clearly indicated in several figures of the drawings, as 2, 3, 4, 5, 6 and 9. In order to facilitate a full inspection of the interior of the retort for the purposes of repair, a manhole construction may be provided, as indicated by *mn* in Figures 2 and 9.

In the operating of the furnace-retort coal is charged to the interior thereof and a substantial portion of the volatile matter in the coal is distilled therefrom. During the distilling, or carbonizing operation as it is frequently called, the coal or charge within the retort is continuously mixed or agitated and it is progressively conveyed toward the discharging end of the retort, from which the coal residue first drops into the discharging opening 94. It subsequently passes the rotary valve and thereafter, when the rotary valve is closed, it can be discharged from the delivery end of the tapering throat member, as desired. The coal is heated within the retort to a temperature approximating from 800 degrees F. to 1200 degrees F. and it will be manifest that the temperature within the combustion flues must at all times exceed said high temperature, if it is desired to regulate the temperature in different parts of the furnace, and this is obtained by the damper control and fuel control heretofore described. The tubular inner wall construction 20 should therefore be of material which will withstand the temperatures mentioned and which will also readily transmit heat from the combustion chambers to the charge within the retort. One material which has been used for this purpose is carborundum-brick, but it will be understood that other materials can be used for this purpose.

Coal treated in a furnace such as is herein described will be uniformly and progressively distilled or carbonized and if the distilling operation is not carried out for a sufficient length of time to remove all of the hydrocarbon volatile matter from the coal there will result a partially distilled coal residue which is uniform in character, as far as distillation characteristics are concerned. The furnace herein described has been designed to effect a partial distillation of a high volatile bituminous coal but it will be understood that it is not limited to this particular purpose as it has a broad application and may be employed for the heat treatment of different kinds of coal having various characteristics.

The improvements herein set forth are not limited to the precise construction and arrangement shown and described for they may be embodied in various forms and modifications without departing from the spirit and scope of the invention.

What I claim is:

65 1. A furnace-retort provided with a

paddle shaft extending longitudinally of and operating in a longitudinally extending retort chamber provided with a combustion chamber divided by vertical transversely extending partitions, and by a vertical longitudinally extending partition along the lower portion of the retort so as to provide combustion flues. 70

2. A furnace-retort as claimed in claim 1 in which the retort chamber consists of a substantially tubular or inverted heart-shaped; longitudinally extending chamber, for the purpose specified. 75

3. A furnace-retort as set forth in claim 1, in which the longitudinally extending dividing partition in the lower portion of the combustion chamber, and the means for supplying fuel and for supplying air for supporting combustion are so constructed that the combustion gases flow in close proximity to the aforesaid partition. 80

4. A furnace-retort as claimed in claim 1 and having a recuperator located below the furnace-retort proper, said recuperator being divided longitudinally into substantially two recuperators by a central longitudinal tunnel in which devices are located for manually controlling the supply of fuel to the heated air of or from each of the recuperators, which fuel and heated air pass to the flues on each side of the vertical longitudinal partition. 90

5. A furnace-retort as claimed in claim 4, in which the furnace side walls are supported upon recuperator side walls, and a longitudinal furnace-retort and combustion chambers between the furnace-retort and the side walls, are supported above the recuperator structure, for the purpose specified. 100

6. A furnace-retort battery according to claim 1 provided with recuperator main walls between adjacent recuperators, and two adjacent furnace side walls supported upon each recuperator main wall, and having furnace retorts and combustion chambers between each pair of adjacent furnace side walls. 110

7. A furnace-retort constructed so as to provide a longitudinally extending retort chamber within which there operates means for mixing or agitating coal therein and for simultaneously conveying the coal along the retort chambers, said furnace-retort also being constructed so as to provide a combustion chamber which is divided into combustion flues by vertically and transversely extending partitions and by a vertically and longitudinally extending partition extending along the lower portion of the retort. 115

8. A furnace-retort constructed so as to provide a longitudinally extending retort chamber having means therein comprising a longitudinally extending paddle-shaft with paddles thereupon for mixing or agitating coal therein and for conveying the coal from the charging end of the retort 125

130

chamber to the discharging end thereof, said furnace-retort having a vertically and longitudinally extending partition along the lower portion of the retort and vertical and transversely extending partitions dividing the combustion chamber into combustion flues, the furnace also being provided with means for controlling the heat condition in each of the combustion flues.

- 10 9. A furnace-retort comprising in combination vertically and transversely extending end walls, vertically and longitudinally extending side walls, a roof extending from end wall to end wall and from side wall to side wall, a retort shell extending from end wall to end wall, which retort shell is spaced from the side walls so that there is provided a combustion chamber between said retort shell and said walls, vertically and transversely extending diaphragms which extend from the retort shell to the side walls and roof in a manner to subdivide the combustion chamber into combustion flues, and valve-controlled means for supplying fuel to the lower portion of each of the combustion flues, there being air ducts or passageways through which air flows into the lower portion of each of the flues to support com-

bustion therein, the flow of products of combustion from the combustion flues being under the control of dampers in passageways leading from the upper portion of said combustion flues.

10. In combination, a substantially airtight longitudinally extending retort, means for feeding coal into the retort at one end thereof, a discharge passageway through which the coal residue is passed from the other end of the retort, means within the retort for agitating the coal or charge within the retort, a furnace providing separated combustion chambers at each side of the retort, vertically and transversely extending partitions or diaphragms which sub-divide each combustion chamber into combustion flues arranged along the retort, means for supplying fuel to said combustion flues, and means for regulating the flow of air to each of the combustion flues.

This specification signed and witnessed 50 this 8th day of May, A. D. 1918.

CHARLES HOWARD SMITH.
